Primary Examiner — Cynthia Underwood(74) *Attorney, Agent, or Firm* — Hamre, Schumann, Mueller & Larson, P.C.(57) **CLAIM**

The ornamental design for a “film sticking device for tablet electronic equipment,” as shown and described.

DESCRIPTION

FIG. 1 is a perspective view 1 of the film sticking device for tablet electronic equipment;

FIG. 2 is a perspective view 2 of the film sticking device for tablet electronic equipment;

FIG. 3 is a front view of the film sticking device for tablet electronic equipment;

FIG. 4 is a back view of the film sticking device for tablet electronic equipment;

FIG. 5 is a left side view of the film sticking device for tablet electronic equipment;

FIG. 6 is a right side view of the film sticking device for tablet electronic equipment; and,

FIG. 7 is a top view of the film sticking device for tablet electronic equipment; and,

FIG. 8 is a bottom view of the film sticking device for tablet electronic equipment.

The broken lines illustrate portions of the article and form no part of the claimed design.

1 Claim, 8 Drawing Sheets**FIG. 1**

FIG. 2

FIG. 3

FIG. 4

FIG. 5

FIG. 6

FIG. 7

FIG. 8
